DESIGN FOR A FRAME FOR A GIRL'S BICYCLE

John R. Morgan, Oak Park, Ill., assignor to Sears,
Roebuck and Co., Chicago, Ill., a corporation
of New York

Application April 24, 1936, Serial No. 62,272

Term of patent 14 years

To all whom it may concern:

Be it known that I, John R. Morgan, a citizen
of the Republic of Guatemala, residing at Oak
Park, in the county of Cook and State of Illinois,
have invented a new, original, and ornamental
Design for a Frame for a Girl's Bicycle, of
which the following is a specification, reference
being had to the accompanying drawing, forming
a part thereof.

Fig. 1 is a side view, and
Fig. 2 is a top plan view of a frame for a girl's
bicycle embodying my new design.

I claim:

The ornamental design for a frame for a girl's
bicycle, as shown.

JOHN R. MORGAN.
